ATTORNEY.

UNITED STATES PATENT OFFICE.

HENRY E. WEBER, OF CANTON, OHIO.

DENTAL CUSPIDOR.

SPECIFICATION forming part of Letters Patent No. 764,022, dated July 5, 1904.

Application filed March 11, 1904. Serial No. 197,616. (No model.)

To all whom it may concern:

Be it known that I, HENRY E. WEBER, a citizen of the United States, residing at Canton, in the county of Stark and State of Ohio, have invented a new and useful Improvement 5 in Dental Cuspidors, of which the following is a specification.

The invention relates to cuspidors for use more particularly in dental surgery, in which 10 there is a constant flow of water from an inlet-tube discharging in the bowl; and the objects of the improvement are to provide means in connection with the main valve for passing the inlet-tube and an overflow-channel through 15 a single aperture in the side of the cuspidor and for connecting the overflow-channel with the drain-pipe below the neck of the cuspidor, so as to make an air-vent of it as well. These 20 objects are attained by the construction and arrangement illustrated in the accompanying drawings, in which—

Figure 1 is a vertical section of the cuspidor, showing the main valve and inlet-tube and overflow-channel; Fig. 2, a horizontal 25 section of the main valve and the inlet-tube and overflow-channel connections; Fig. 3, a detached perspective longitudinal section of the valve-case; Fig. 4, a detached perspective section of the connecting-sleeve; and Fig. 5 a 30 detached perspective view of the inlet-tube, the ring-screw, and the packing-washer.

Similar numerals refer to similar parts throughout the drawings.

The cuspidor-bowl 1 is preferably made of 35 glass, and its neck 2 is suitably connected with the drain-pipe 3. The overflow-pipe 4 is connected with the drain-pipe, preferably by the tubular bracket 5, which bracket also furnishes a support for the main water-supply 40 pipe 6. The main-valve case 7 is provided with the tubular extension 8, and it is attached on the side of the bowl by means of the connecting-sleeve 9, having the rim-flange 10, which sleeve is adapted to be entered 45 through the aperture 11 in the side wall of the bowl and to be screwed into the tubular extension of the valve-case. The intervening washers 12 are preferably provided on each side of the wall of the bowl to make a tight

and substantial joint with the sleeve-flange 50 and the case extension on each side thereof.

The main supply-pipe 6 is connected in the lower end of the usual through-passage 13 of the valve-case, in the upper end of which passage is connected the tubular post 14, on 55 which is attached the usual tumbler-holder 15, and to the tubular part of the post is connected the supply-pipe 16, leading to the usual tumbler-faucet and saliva ejector-valves. (Not shown.) The axial valve-port 17 leads 60 from the outer side of the through-passage to the valve-chamber 18, from which chamber the lateral ports 19 pass back on each side of the through-passage and converge into the axial inlet-port 20, which opens into the tu- 65 bular extension of the case, in which port is inserted the end of the straight shank of the inlet-tube 21.

The external annular shoulder 22 is provided near the end of the inlet-tube, which 70 shoulder is adapted to bear against the valve-case around the inlet-port, preferably with the packing-washer 23 intervening to prevent any leakage, and on the inlet-tube at a point within the connecting-sleeve is also provided 75 the opposing external annular shoulder 24, against which shoulder is brought to bear the rotatable ring 25, which is adapted to be screwed into the connecting-sleeve, by which means the inlet-tube is readily connected with 80 the valve or detached therefrom when the valve is connected with the cuspidor-bowl without any rotation of the tube itself, such a rotation being prohibited by reason of the peculiar shape of the tube and the overhang- 85 ing rim 26 of the bowl.

The overflow-pipe 4 is connected in the lower side of the tubular extension of the valve-case, and the apertures 27 are provided in the ring-screw around the inlet-tube, so that water is 90 free to overflow from the bowl through these apertures and through the channel 28, formed around the inlet-tube in the connecting-sleeve and tubular extension of the valve-case, and into and through the overflow-pipe into the 95 drain-pipe, and, conversely, any air which may accumulate in the drain-pipe is free to escape through the overflow-pipe and the same chan-

nel and apertures. The apertured ring-screw also acts as a screen for the outlet-channel.

What I claim as my invention, and desire to secure by Letters Patent, is—

- 5 1. A cuspidor-bowl having an aperture in its side, a valve-case having a tubular extension and an axial port opening therein, a sleeve having a rim-flange and adapted to be entered through the aperture and screwed into the
- 10 tubular extension, an inlet-tube adapted to be entered in the axial port, a rotatable apertured ring on the tube adapted to be screwed into the sleeve, there being opposed annular shoulders on the tube adapted to bear against the valve-case and the ring-screw, and a pipe leading from the tubular extension.
- 15

2. A cuspidor-bowl having an aperture in its side, a sleeve in the aperture, a valve-case connected with the sleeve having an axial port, a tube in the sleeve adapted to connect with the port and to bear against the case, and a rotatable apertured ring on the tube adapted to be screwed into the sleeve, there being an annular shoulder on the tube adapted to bear against the ring-screw.

In testimony whereof I have signed my name to this specification in the presence of two subscribing witnesses.

HENRY E. WEBER.
